(57) **CLAIM**

The ornamental design for a combination rocking horse,
desk, and highchair, as shown and described.

DESCRIPTION

FIG. 1 is a side elevational view of the new and improved
combination rocking horse, desk, and highchair illustrating
my new design.

FIG. 2 a front elevational view thereof;

FIG. 3 is a rear elevational view thereof;

FIG. 4 is a top view thereof;

FIG. 5 is a bottom view thereof;

FIG. 6 is a perspective illustration of my new design
oriented in the rocking horse mode.

FIG. 7 is a perspective illustration of my new design
oriented in the desk mode; and,

FIG. 8 is a perspective illustration of my new design
oriented in the highchair mode.
